DESIGN FOR A GAS MASK

Thomas A. O'Leary, Pittsburgh, Pa., assignor to
Acme Protection Equipment Company, a cor-
poration of Pennsylvania

Application October 6, 1937, Serial No. 71,997

Term of patent 14 years

To all whom it may concern:

Be it known that I, Thomas A. O'Leary, a citizen of the United States and a resident of Pittsburgh, in the county of Allegheny and State of Pennsylvania, have invented a new, original, and ornamental Design for a Gas Mask, of which the following is a specification, reference being had to the accompanying drawing, forming a part thereof, wherein:

Figure 1 is a front elevation of the mask. Fig. 2 is an elevation with the line of observation at right angles to one of the lens.

I claim:

The ornamental design for a gas mask as shown.

THOMAS A. O'LEARY.
